UNITED STATES PATENT OFFICE

110,150

DESIGN FOR AN AUTOMOBILE AERIAL

Robert D. McIntosh, River Forest, Ill., assignor
to The Imperial Brass Manufacturing Company, Chicago, Ill., a corporation of Illinois

Application August 28, 1937, Serial No. 71,369

Term of patent 3½ years

To all whom it may concern:

Be it known that I, Robert D. McIntosh, a citizen of the United States, residing at River Forest, in the county of Cook and State of Illinois, have invented a new, original, and ornamental Design for an Automobile Aerial, of which the following is a specification, reference being had to the accompanying drawing, forming a part thereof.

In the drawing:

Fig. 1 is a top plan view; and

Fig. 2 is a front elevational view of the automobile aerial, showing my design.

Since the body portion of the aerial is uniform throughout, a side elevational view would appear precisely like the top plan view shown in Figure 1.

I claim:

The ornamental design for an automobile aerial, as shown and described.

ROBERT D. McINTOSH.
